UNITED STATES PATENT OFFICE.

JOHN A. OSTENBERG, OF CAMPBELL, CALIFORNIA.

MAGNETO-DRIVE FOR INTERNAL-COMBUSTION ENGINES.

1,196,270.

Specification of Letters Patent. Patented Aug. 29, 1916.

Application filed September 13, 1915. Serial No. 50,469.

To all whom it may concern:

Be it known that I, JOHN A. OSTENBERG, a citizen of the United States, and resident of Campbell, in the county of Santa Clara 5 and State of California, have invented a certain new and useful Improvement in Magneto-Drives for Internal-Combustion Engines, of which the following is a specification.

10 My invention relates to an improvement in a magneto drive for internal combustion engines, and the object of my invention is to produce a simple effective device that will cause the magneto to produce a spark of sufficient intensity to fire the initial charge in starting when the engine is turned over slowly, and also to automatically retard the timing of the spark so as to avoid back firing, and to automatically advance the spark 15 and throw the spark intensifying apparatus out of service when the engine is properly started and has acquired sufficient speed.

In the drawings which form a part hereof 25 and in which similar reference characters designate similar parts throughout the several views, Figure 1 is a perspective view of my device in position, parts being broken away. Fig. 2 is a diagrammatic plan view 30 of the principal working parts, parts being broken away. Fig. 3 is a vertical section showing the connections of the spring and Fig. 4 a perspective view of the interrupter.

Referring now more particularly to the 35 drawings, 1 indicates a portion of a bracket attached to the engine and upon which magneto 2 is mounted. To armature shaft 3 of magneto 2 is fixed notched bar 3^a having notches 3^b and 3^c formed in the ends thereof. 40 To the upper end of driving shaft 4, mounted in bearing 4^a, is secured plate 5 having pins 6 and 7 fixed diametrically opposite each other in the upper surface thereof and of sufficient length to engage notched bar 3^a. 45 A coiled spring 8 is shown having one end thereof fixed in plate 5 and the opposite end fixed in notched bar 3^a.

At 9 is shown the throttle arm of the governor which is revolvably mounted on pin 9^a 50 fixed in the engine casing, and at 9^b and 9^c are spur gear sectors operating shaft 9^d upon

which carburetor valve 9^e is mounted and which is operated by the rocking motion of the throttle arm 9. Secured to bracket 1 are bearings 10, 11 and 12 having a vertical 55 shaft 13 revolvably mounted therein, the upper end of said shaft 13 being bent at right angles to form arm 13^a and connected to timing arm 14 of magneto 2 by link 15. Near the lower end of shaft 13 and in a 60 position to swing freely over throttle arm 9 is secured lever 16, the same being held in the position shown by spring 16^a. In the top of throttle arm 9 and in approximately the position shown is fixed a pin 17 65 having its upper end flattened as shown at 18. Rigidly fixed in the outer side of lever 16 is a catch as shown at 19 in such a position as to engage end 18 of arm 17 when lever 16 is swung outwardly as shown in 70 dotted lines at 20.

At 21 is shown a notch formed in the side of shaft 13 just below bearing 11 and in such a position as to engage interrupter 22 when turned toward bracket 1 by lever 16. 75 Interrupter 22 is secured to bracket 1 by bolts 23 and is formed as shown in Fig. 4 with a notch cut therein at 22^a to engage pins 6 and 7 as hereinafter described.

I will now describe in detail the operation of my device, the engine being quiet and the various parts of my device being in the positions shown in solid lines in the drawings. Lever 16 is thrown by hand into the position shown in dotted lines at 20 80 and held in this position by catch 19 engaging end 18 of pin 17. This operation causes timing arm 14 to be thrown into the position 14^a and allows interrupter 22 to advance to position 22^a. The engine now being started 90 by hand, the revolving of the armature shaft 3 causes one notch as 3^c in bar 3^a to catch on notch 22^a in interrupter 22. As the armature shaft 3 continues to revolve pins 6 and 7 move away from bar 3^a until 95 pin 6 strikes the curved end 22^b of interrupter 22 and thus allows spring 8 to revolve the armature shaft at a high rate of speed for a portion of its revolution or until bar 3^a again strikes pins 6 and 7. This 100 adjustment and operation as described produces a spark of the required intensity to

fire the initial charges in the cylinder just as the piston passes the dead center of the compression stroke. The engine now being started the upward movement of the governor causes the throttle arm 9 to move in the direction indicated by the arrow and of course giving pin 17 the same movement. This pivotal movement of throttle arm 9 and pin 17 disengages pin 17 from catch 19 whereupon spring 16^a forces lever 16 back to its normal position, the cam like action of shaft 13 at its notched portion 21 throws interrupter 22 back so as not to engage the notches in bar 3^a as it revolves, and advances the spark to its normal time.

It is understood that while I have herein described and illustrated a device adapted for use with a two cylinder engine, minor changes in construction and operation may be made within the scope of the appended claims, as for instance the device may be adapted for use with a one cylinder engine or an engine with more than two cylinders.

Having thus described my invention what I claim as new and desire to secure by Letters Patent, is:—

1. A magneto drive for internal combustion engines, comprising a yieldingly connected driving shaft and armature shaft, one or more stops positioned on said driving shaft, means secured to said armature shaft in such a position as to engage said stops, an adjustable interrupter for said arm, and governor controlled means for adjusting said interrupter.

2. A magneto drive for internal combustion engines, comprising a yieldingly connected driving shaft and armature shaft, one or more stops positioned on said driving shaft, an arm secured to said armature shaft in such a position as to engage said stops, an adjustable interrupter for said arm mounted independently of said magneto drive and in operative relation thereto, and governor controlled means for adjusting said interrupter.

3. A magneto having a timing arm, a yieldingly connected driving shaft and armature shaft, one or more stops positioned on said driving shaft, an arm secured to said armature shaft in such a position as to engage said stops, an adjustable interrupter for said arm, and governor controlled means for simultaneously adjusting said interrupter and said timing arm.

4. A magneto drive for internal combustion engines, comprising a yieldingly connected driving shaft and armature shaft, one or more stops positioned on said driving shaft, an arm secured to said armature shaft in such a position as to engage said stops, an interrupter capable of being thrown into and out of operative engagement with said arm, manually operated means for oper-

atively positioning said interrupter and 65 governor controlled means for automatically removing said interrupter from an operative position.

5. A magneto drive for internal combustion engines, comprising a yieldingly connected driving shaft and armature shaft, one or more stops positioned on said driving shaft, an arm secured to said armature shaft in such a position as to engage said stops, an interrupter for said arm, mounted 70 independently of said magneto drive and having a notch formed therein to engage said arm and an outwardly turned end adapted to engage said stops, and governor controlled means adapted to remove said interrupter from engagement with said stops at a predetermined period.

6. A magneto drive for internal combustion engines having an adjustable interrupter mounted independently thereof and 85 in operative relation thereto, a governor operatively connected thereto, a shaft yieldingly mounted adjacent to said magneto drive and adapted to adjust said interrupter, means for locking said shaft to said governor when quiescent and releasing said shaft 90 when in operation.

7. The combination of a magneto having a spark retarding and intensifying device attached thereto and a mechanism for rendering said device operative and inoperative, said device comprising an adjustable interrupter mounted independently of said magneto drive and in operative relation thereto, a shaft yieldingly mounted adjacent thereto 100 having one end eccentrically connected to the timing arm of said magneto and adapted to adjust said interrupter, an arm secured to said shaft and means for attaching said arm to said governor when said governor is 105 quiescent and releasing said arm when in operation.

8. The combination with a magneto having a spark retarding and intensifying device attached thereto and a governor operatively connected thereto, of a member secured in the upper surface of said governor, an interrupter, a yieldingly mounted shaft operating eccentrically thereagainst and eccentrically connected to the timing arm of 115 said magneto and having an arm capable of being thrown into and out of engagement with said member.

9. The combination with a magneto, a spark intensifying device and a governor 120 operatively positioned with relation to each other, of governor controlled means for rendering said intensifying device operative while said governor is quiescent and inoperative when said governor is in operation.

10. The combination with a magneto having a spark timing device attached thereto and a governor operatively positioned with

relation thereto, of governor controlled means for holding said spark timing device in a spark retarding position while said governor is quiescent and advancing said 5 spark timing device while said governor is in operation.

In testimony whereof I have hereunto af-

fixed my signature in the presence of two subscribing witnesses.

JOHN A. OSTENBERG.
